(57) **CLAIM**

The ornamental design for a kernel removal device, as shown, and described.

DESCRIPTION

FIG. 1 is a front view of the kernel removal device;
FIG. 2 is a rear view of the kernel removal device;
FIG. 3 is a side view of the kernel removal device;
FIG. 4 is a top view of the kernel removal device; and,
FIG. 5 is a perspective view of the kernel removal device.
